United States Patent Office.

GEORGE W. RUCKER, OSWALD C. SWAN, AND THOMAS W. RUCKER, OF ST. LOUIS, MISSOURI.

Letters Patent No. 105,981, dated August 2, 1870.

IMPROVED MACHINE FOR PRESSING AND SHEETING TOBACCO.

The Schedule referred to in these Letters Patent and making part of the same.

To all whom it may concern:

Be it known that we, GEORGE W. RUCKER, OSWALD C. SWAN, and THOMAS W. RUCKER, all of the city and county of St. Louis, State of Missouri, have invented a new and useful improved Apparatus for Pressing Tobacco, of which the following is a full, clear, and exact description, reference being had to the annexed drawing making a part of this specification, in which—

Figures 1 and 2 represent side views of different parts of our apparatus.

Figure 3 represents a plan of fig. 2.

Similar letters indicate like parts.

In the ordinary manner of manufacturing tobacco there is much loss of time and great labor employed in rolling the leaf, preparatory to prizing in the cells, and, also, there is great waste in the material, and much refuse created in the cutting of the prized tobacco, so as to prepare it for the caddies.

To remedy these defects, and at the same time do the work much better and quickly, is the object of our invention, which we are about to describe.

We construct a box, A, without bottom or top, having only four sides, which are put together by rods *a a'*, &c., fig. 1, having heads on one end and nuts on the other, so that, by merely loosening the latter, the ends may be taken out or slid up, as indicated by the dotted line in the figure. This must be made strong enough to withstand great lateral pressure. This box when in use, rests on a platform, B, attached to a frame, G, and through the cross-piece of this frame is passed a screw, D, as seen, and having a slot, e, through which to pass a lever which operates it.

Of course the ends of B must rest firmly, and this may be accomplished either by placing supports under each end, or sinking the frame G in the earth or the flooring till it is flush with B.

Numerous plates, preferably made of metal, are made to fit exactly in the inside of A, as seen at *b b'*, &c.

On another frame, E, figs. 2 3, is arranged a plate, F, so that it can be slid in and out, as indicated by the dotted line in fig. 2, suitable mortises being provided for it to run in, it resting, however, on the bed V of the frame.

Around the two sides of this plate are perforations *o o'*, &c., so arranged that when the tooth of the spring catch R, figs. 2, 3, (the spring being plainly seen in the former figure,) drops into each, it shall hold the plate in such a position that one of the grooves or channels 1 2 3, &c., cut at right angles to each other on the face of the plate shall be directly under a circular knife, S, hereafter to be described. This plate is made so that it may be taken entirely out and put

back, so that each series of channels may be, in turn, in the line of the movement of the knife; and, as in practice, this plate will not be square in the portion intersected by the grooves, there will be a vacant space at one end, as seen at *x*, fig. 3, as, of course, the exterior of the plate must be exactly square, in order to allow it to be turned about, as described.

Another frame, P, figs. 2, 3, sliding in the mortised cross-pieces *m m'*, figs. 2, 3, carries the shaft N of the circular knife S, the latter being so hung as to run in the grooves or channels cut as described in the plate F, and plainly seen in fig. 3.

By sliding this plate in and out, and reversing as described, of course the knife may be made to travel successively in each of the grooves; or, if it is preferred, several blades or knives, corresponding to the number of the grooves, may be attached to the revolving shaft, in which case the plate need not be moved, except to reverse it, all the parallel cuttings being made at the same time; but we prefer the single knife, as the other would require an increase of power not desirable.

The mode of using our apparatus is as follows:

The tobacco having been treated in the usual way, up to the point where the usual rolling commences, we dispense with this and put the leaves directly into the box A. When we have enough in it, we insert above the tobacco one of the plates *b*, as seen, and continue the operation of placing alternately the tobacco and plates till we have completely filled the box, using the lever-screw D to assist the filling, and to prize the tobacco into compact sheets, as is done in the old cell press. When it is sufficiently prized, the nuts of the rods are loosened, and the ends of the box slid up till a layer or sheet of the tobacco can be removed, which is then placed on the plate F, and, by means of the revolving knife S, cut into strips corresponding to the spaces between the channels on the plate; then the knife is drawn back till the frame P is in the position indicated by the dotted lines in fig. 3, and the plate F is reversed, and the cutting again carried on. This leaves the sheets of tobacco in the shape of lumps corresponding to the divisions of the plate F, which are then taken, and, in the usual manner, prized into the caddies.

The manner in which the grooves are laid out on the plate F is regulated by the size of the lump into which it is proposed to cut the tobacco, and the amount of tobacco put between each plate in the box A is regulated by weight, the weight being determined by the number, size, and weight of the lumps into which it is proposed to cut the sheets.

The leaf, when put into the box, may be either wet or dry, which is not the case when the process of roll-

ing is resorted to, for then the tobacco must be wet. It is evident that there can be no refuse or waste from the cutting, as the box A and the plate on which the sheets are cut are made exactly the same in size.

As an illustration of the construction of an apparatus of this kind, we will give the dimensions and operation of one now in use in our factory.

The box A is four feet high, and twenty-four by thirty-six inches inside measurement. It makes nineteen sheets, using, of course, twenty boards or plates. Each sheet is cut by the knife, we using but one, into forty-eight lumps, six inches by three, which is the dimension of the squares or spaces on the plate F. With this apparatus one man and a boy can work twelve hundred pounds of tobacco in a day, fully ten times as much as by the old process.

We, of course, do not claim there is anything new in prizing tobacco into sheets, or in cutting it afterward into lumps, since both operations have long been practiced, nor do we claim any originality in the man-

ner of operating the prizing-screw, or of disposing of the lumps after they are cut by the knife as described; but

What we do claim as our invention, and desire to secure by Letters Patent, is—

In connection with the press-box A of a tobacco-press, constructed substantially as shown, the herein-described cutting machinery, consisting of the stationary frame E and catch R, the sliding frame P, carrying the shaft N and circular knife S, and the sliding plate F, provided with perforations o o', and the longitudinal and transverse grooves 1, 2, 3, &c., all constructed and arranged for joint operation, substantially as and for the purpose specified.
